Filed Oct. 12, 1971, Ser. No. 188,662

Term of patent 7 years

Int. Cl. D3—02

U.S. Cl. D86—10 G

FIG. 2

FIG. 1 is a side view of a casing for an eyeliner brush and an eyelash brush showing my design; and

FIG. 2 is an end view, both ends being similar.

The characteristic feature of the design resides in the particular pictorial surface ornamentation as shown, the remainder of the surface being plain and unornamented.

I claim:

The ornamental design for a casing for an eyeliner brush and an eyelash brush, as shown and described.
